CARRYING CASE FOR BINOCULARS OR THE LIKE

Yoshiaki E. Motokane, Culver City, Calif., assignor to Craig Panorama, Inc., Los Angeles, Calif., a corporation of California

Filed Apr. 15, 1963, Ser. No. 74,429

Term of patent 14 years

(Cl. D87—5)

FIG. 1 is a front perspective view of a carrying case for binoculars or the like, showing my new design, with the hinged cover in an open position.

FIG. 2 is a side elevational view with the cover in a closed position, and the handle being omitted for convenience of illustration.

FIG. 3 is a front elevational view thereof.

The dominant features of the design are shown in the drawings in full lines. The face of the article that is not shown is similar in shape and contour to the face that is shown.

I claim:

The ornamental design for a carrying case for binoculars or the like, substantially as shown and described.
